No. 621,249.

Patented Mar. 14, 1899.

L. O. HENGGI.

JACK.

(No Model.)

(Application filed Dec. 12, 1898.)

UNITED STATES PATENT OFFICE.

LEWIS O. HENGGI, OF VERONA, PENNSYLVANIA.

JACK.

SPECIFICATION forming part of Letters Patent No. 621,249, dated March 14, 1899.

Application filed December 12, 1898. Serial No. 699,050. (No model.)

To all whom it may concern:

Be it known that I, LEWIS O. HENGGI, a citizen of the United States, residing at Verona, in the county of Allegheny and State of Pennsylvania, have invented certain new and useful Improvements in Jacks; and I do hereby declare the following to be a full, clear, and exact description of the invention, such as will enable others skilled in the art to which it appertains to make and use the same.

This invention relates to lifting-jacks, and is particularly intended as an improvement upon the construction shown in Patent No. 536,594, dated April 2, 1895, the principal object of the present invention being to provide for a step-by-step lowering of the jack, which cannot be accomplished with the construction shown in said patent.

It is apparent that in the use of a lifting-jack it is often desirable to lower the load carried by it to a slight extent or a little at a time, and in evolving my invention with this end in view I have added certain features to a lifting-jack of the type shown in the patent above mentioned, whereby upon effecting a slight adjustment manipulation of the operating handle or lever will result in a lowering of the rack-bar tooth by tooth.

With the above-stated object in view the invention consists in certain novel features of construction and combinations of parts, the essential elements of which are recited in the appended claims, and a preferred form of embodiment of which is illustrated in the accompanying drawings, forming part of this specification.

Of said drawings, Figure 1 represents the lifting-jack in side elevation with the parts adjusted for the ordinary operation of lifting and the operating handle or lever elevated. Fig. 2 shows the upper portion of the lifting-jack in section, the same adjustment obtaining as in Fig. 1, but the operating lever or handle being represented as depressed. Fig. 3 shows a sectionalized side elevation of the upper portion of the lifting-jack with the operating handle or lever elevated and the parts adjusted for step-by-step lowering of the rack-bar. Fig. 4 is a view similar to Fig. 3, the operating lever or handle, however, being depressed and the relation of parts being correspondingly changed. Fig. 5 shows the parts

which characterize my invention assembled and in perspective under the adjustment shown in Figs. 1 and 2. Fig. 6 represents the manipulative member of my attachment in perspective. Fig. 7 is a horizontal section taken on the line VII VII of Fig. 1.

The casing or hollow standard *a*, the rack-bar *b*, the operating handle or lever *c*, and the lifting-pawl *d* are all of much the same form of construction as shown in the patent hereinbefore mentioned, and the holding pawl or catch *e* is located and pivoted in substantially the same manner, so as to gravitate into engagement with the teeth of the rack-bar. The operation of lifting is practically the same as with the construction shown in said patent, raising and lowering of the handle-lever *c* resulting in the pawl *d* successively engaging the teeth of the rack and the pawl *e* dropping behind the same as the rack-bar is pushed upwardly by the pawl *d*. The latter is provided with a pin *d'*, as in the construction shown in the patent referred to, which pin projects through an opening of suitable size and shape in the side of the casing or hollow standard, and this pawl by means of said pin can be withdrawn from engagement with the rack and brought to a position where upon upward movement it will engage a socket *e'*, formed in the lower end of the upper pawl *e*, and will thereby cause the disengagement of the latter from the rack-bar, so as to leave the same free to drop to its lowest position, as described in the before-mentioned patent. As hereinbefore stated, however, it is often desirable to lower the rack-bar little by little, and for the accomplishment of this object I pivot to the upper pawl, between the arms thereof, as indicated at *f*, an arched swinging piece *f'*, having a longitudinal bifurcation *f''*. Projections in the form of screws *f'''*, entered in the outer sides of the members of the bifurcated portion of said swinging piece, constitute supports for the upper ends of a pair of spiral springs *g*, formed with eyes surrounding portions of said screws between the heads of the same and the sides of the swinging piece, and being also formed with similar eyes at their lower ends surrounding and suitably confined upon protruding portions of the pin *d'* in the lower pawl *d*. The said spiral springs are normally

closed, and up-and-down movement of the lower pawl *d* oscillates the swinging piece on its pivot without affecting the upper pawl, as illustrated by Figs. 1 and 2, the swinging piece in its lowermost position abutting the pawl *e*, whereas when the operating-lever has been depressed there is a considerable space between said swinging piece and the outer or top surface *e*² of the lower portion or cross-bar of the said pawl.

A rotatable locking-piece or turn-button occupies the bifurcation of the swinging piece and is pivoted or swiveled to the pawl *e*, said turn-piece comprising a boss *h*, which bears against the surface *e*² and through which a screw *h*' passes, said screw entering a screw-threaded socket in the pawl *e* and constituting a bearing or pivot for the turn-button, which further comprises lateral projections *i* on opposite sides of the boss *h*, at the base of the same, said projections being triangular in end elevation and beveled on their upper sides, as shown at *i*', to provide cam-surfaces rising from the outer lower corners of the projections and merging into the upper sloping sides of the latter, which result from the triangular formation thereof. Projections *j* on opposite sides of the boss *h*, at the upper end thereof, are formed with portions *j*', confronting the projections *i* and of similar formation thereto, being triangular in end elevation and their under surfaces being beveled, as shown at *j*², so as to form cam-surfaces merging into the sloping surfaces which result from the triangular formation. Thumb-pieces *j*⁴ rise from the upper sides of the projections *j* to provide convenient means for manipulating the turn-button. Normally the latter will stand in the direction of the bifurcation of the swinging piece and will offer no obstruction to oscillation of the same; but when said turn-button moves through a quarter of a circle it will be seen that its lower projections *i* are carried under the swinging piece, while its projections *j* are carried over the same and oscillation of the swinging piece on its pivot will be prevented. This quarter-turn of the button is made when it is desired to lower the rack-bar step by step. With the parts in the position shown in Fig. 1 such manipulation of the turn-button will cause two of the cam-surfaces *i*' on the lower projections *i* to operate against the under sides of the members of the bifurcated portion of the swinging piece, so as to force the latter away from the surface *e*², as illustrated in Fig. 3, and this movement of the swinging piece will disengage the lower pawl *d* from the rack-bar through the medium of the spiral springs, which, it will be seen, constitute links of a toggle of which the lower pawl is a member, said toggle being partially straightened by the above-described operation and this straightening necessarily resulting in disengagement of the pawl from the rack and, moreover, resulting in the springs being put

under tension. This adjustment of parts having been effected, depression of the operating-lever first has the effect of moving the end of the lower pawl past the shoulder of the tooth it has previously engaged and behind the tooth next above, the closing of the springs allowing this movement of the pawl to take place without affecting the upper pawl and the toggle form of connection insuring the movement of the lower pawl toward the rack-bar. Further upward movement of the pawl *d*, produced by depression of the operating-lever, will cause the disengagement of the upper pawl from the rack, as shown in Fig. 4, outward movement of the swinging piece being prevented by the upper projections *j* of the turn-button and outward movement of the pawl necessarily ensuing through the medium of the springs, which now constitute links connecting the lower pawl with the upper pawl. A lowering of the rack-bar the extent of one tooth is the necessary result of the above-described operation. Should the turn-button be manipulated when the parts are in the position shown in Fig. 2, the cam-surfaces *j*² of the upper projections by operating against the upper sides of the bifurcated portion of the swinging piece will effect the disengagement of the upper pawl from the rack, so that upon raising the operating handle or lever the rack-bar will be lowered to the extent of one tooth, the consequent lowering of the pawl *d* being necessarily accompanied by movement of the upper pawl into position for engagement with the rack.

It will be seen that a construction such as above described is well calculated to fulfil the object primarily stated. However, it is to be understood that the invention is capable of embodiment in other forms than that here shown, and therefore in the claims which follow essential elements of the invention are recited without restriction to details of construction.

Having thus fully described my invention, what I claim as new, and desire to secure by Letters Patent of the United States, is—

1. In a jack, the combination of a standard, a rack-bar slidably fitted to the same, a lever pivoted to the standard and carrying an upstanding pivotal pawl adapted to engage the rack-bar, an upper pendent pawl pivoted to the standard and adapted to engage the rack, and a link connection between the two pawls whereby rocking of the lever alternately engages them with the rack-bar to permit step-by-step lowering of the same.

2. In a jack, the combination of a standard, a rack-bar slidably fitted to the same, a lever pivoted to the standard and carrying an upstanding pivotal pawl adapted to engage the rack-bar, an upper pendent pawl pivoted to the standard and adapted to engage the rack, and a link connection between the two pawls together with a lock whereby the link connection can be made effective to produce al-

ternate engagement of the pawls with the rack-bar under rocking of the lever, substantially as and for the purpose described.

3. In a jack, the combination of a standard, 5 a rack-bar slidingly fitted to the same, a lever pivoted to the standard and carrying an up-standing pivotal pawl adapted to engage the rack-bar, an upper pendent pawl pivoted to the standard and adapted to engage the rack, 10 a swinging piece on said upper pawl, a link connecting said swinging piece with the lower pawl, and a locking-piece for said swinging piece manipulative to lock the latter to the upper pawl whereby rocking of the lever may 15 produce alternate engagement of the pawls with the rack-bar, substantially as and for the purpose described.

4. In a jack, the combination of a standard, 20 a rack-bar slidingly fitted to the same, a lever pivoted to the standard and carrying an up-standing pivotal pawl adapted to engage the rack-bar, an upper pendent pawl pivoted to the standard and adapted to engage the rack, a swinging piece on said upper pawl, a link 25 connecting said swinging piece with the lower pawl, and a locking-piece for said swinging piece manipulative to lock the latter to the upper pawl whereby rocking of the lever may produce alternate engagement of the pawls 30 with the rack-bar, said locking-piece having a portion which acts against the swinging piece to initially disengage one pawl from the rack.

5. In a jack, the combination of a standard, 35 a rack-bar slidingly fitted to the same, a lever pivoted to the standard and carrying an up-standing pivotal pawl adapted to engage the rack-bar, an upper pendent pawl pivoted to the standard and adapted to engage the rack, 40 a swinging piece on said upper pawl, a link connecting said swinging piece with the lower pawl, and a locking-piece having a double cam formation for engagement with opposite sides of the swinging piece to disengage either 45 pawl from the rack-bar in locking the swinging piece to the upper pawl, substantially as and for the purpose described.

6. In a jack, the combination of a standard, 50 a rack-bar slidingly fitted to the same, a lever pivoted to the standard and carrying an up-standing pivotal pawl adapted to engage the rack-bar, an upper pendent pawl pivoted to the standard and adapted to engage the rack, a swinging piece on said upper pawl, a link 55 connecting said swinging piece with the lower pawl, and a locking turn-piece having a double cam formation for engagement with opposite sides of the swinging piece to disengage either pawl from the rack in locking the 60 swinging piece to the upper pawl, substantially as and for the purpose described.

7. In a jack, the combination of a standard, 65 a rack-bar slidingly fitted to the same, a lever pivoted to the standard and carrying an up-standing pivotal pawl adapted to engage the rack-bar, an upper pendent pawl pivoted to the standard and adapted to engage the rack,

a swinging piece of bifurcated form on said upper pawl, links connecting said swinging piece with the lower pawl, and a turn-piece 70 swiveled to the upper pawl and occupying the bifurcation of the swinging piece, said turn-piece having confronting beveled shoulders or inclined faces on each side for engagement with opposite sides of the swinging piece to lock the same to the pawl and to initially disengage one of the pawls from the rack-bar, substantially as and for the purpose described.

8. In a jack, the combination of a standard, 80 a rack-bar slidingly fitted to the same, a lever pivoted to the standard and carrying an up-standing pivotal pawl adapted to engage the rack-bar, an upper pendent pawl pivoted to the standard and adapted to engage the rack, a swinging piece normally seating downwardly against an upper surface or shoulder of the upper pawl, a spring connecting said swinging piece with the lower pawl and forming a toggle therewith, and means for moving 85 the swinging piece away from the shoulder against which it normally lies and thereby straightening the said toggle, together with means for locking the swinging piece against further outward movement relative to the 90 upper pawl, substantially as and for the purpose described.

9. In a jack, the combination of a standard, 95 a rack-bar slidingly fitted to the same, a lever pivoted to the standard and carrying an up-standing pivotal pawl adapted to engage the rack-bar, an upper pendent pawl pivoted to the standard and adapted to engage the rack, and a link connection between the two pawls 100 in the form of a spring whereby rocking of the lever alternately engages them with the rack-bar to permit step-by-step lowering of the same.

10. In a jack, the combination of a standard, 105 a rack-bar slidingly fitted to the same, a lever pivoted to the standard and carrying an up-standing pivotal pawl adapted to engage the rack-bar, an upper pendent pawl pivoted to the standard and adapted to engage the rack, a swinging piece on said upper pawl, a link 110 connecting said swinging piece with the lower pawl, and a locking-piece for said swinging piece manipulative to lock the latter to the upper pawl whereby rocking of the lever may produce alternate 115 engagement of the pawls with the rack-bar, substantially as and for the purpose described.

11. In a jack, the combination of a standard, 120 a rack-bar slidingly fitted to the same, a lever pivoted to the standard and carrying an up-standing pivotal pawl adapted to engage the rack-bar, an upper pendent pawl pivoted to the standard and adapted to engage the rack, a swinging piece of bifurcated form on said 125 upper pawl, links in the form of springs connecting said swinging piece with the lower pawl, and a turn-piece swiveled to the upper pawl and occupying the bifurcation of the

swinging piece, said turn-piece having confronting beveled shoulders or inclined faces on each side for engagement with opposite sides of the swinging piece to lock the same 5 to the pawl and to initially disengage one of the pawls from the rack-bar, substantially as and for the purpose described.

In testimony whereof I affix my signature in presence of two witnesses.

LEWIS O. HIENGGI.
